MABEL AARON, OF STOCKTON, CALIFORNIA.

BROILER AND BAKING ATTACHMENT FOR GAS-STOVES.

1,143,603:

Specification of Letters Patent. Patented June 22, 1915.

Application filed January 25, 1915. Serial No. 4,194.

To all whom it may concern:

Be it known that I, MABEL AARON, a citizen of the United States, residing at Stockton, in the county of San Joaquin, State of California, have invented certain new and useful Improvements in Broiler and Baking Attachments for Gas-Stoves; and I do declare the following to be a clear, full, and exact description of the same, reference being had to the accompanying drawings, and to the characters of reference marked thereon, which form a part of this application.

This invention relates to improvements in attachments for gas stoves and particularly to an attachment for use in broiling and baking, whereby such last mentioned operations will be carried on directly over the open flame burners without the necessity of using an oven or other additional structure.

20 The attachment includes a general frame in which may be used broilers, baking pans, waffle pans and all the various other forms of utensils used for cooking purposes.

A further object of the invention is to 25 produce a simple and inexpensive device and yet one which will be exceedingly effective for the purposes for which it is designed.

These objects, I accomplish by means of such structure and relative arrangement of 30 the parts as will fully appear by a perusal of the following specification and claims.

On the drawings, similar characters of reference indicate corresponding parts in the several views.

35 Figure 1 is a top plan view of a two-burner gas stove showing the application of my improved attachment thereto. Fig. 2 is a side elevation of the same. Fig. 3 is a fragmentary view, partly in section, taken 40 on a line X—X of Fig. 2. Figs. 1, 2 and 3 show a broiler in connection with the gas stove. A sectional view of this broiler is shown in Fig. 4. Figs. 5 and 6 are sectional views of a waffle pan and biscuit pan, respectively, for use with my attachment. Fig. 7 is a sectional view of a toaster to be 45 used in connection with my attachment.

Referring now more particularly to the characters of reference on the drawings, the 50 numeral 1 designates the rectangular frame of the stove which of course, when the burner is used for ordinary cooking purposes, would be provided with suitable grates underneath which would be the burner 2. In using my improved attachment 55 however, these grates are removed so I do

not show them here. My improved attachment comprises a rectangular frame 3 adapted to rest on the edges of the stove 1. On the under side of this frame 3 are spaced dependent U-shaped members 4 supporting roller guide members 4^a. On each edge of the frame 3 is an upwardly extending guide flange 6.

The numeral 7 designates a carrier projecting through slots 5, in the frame 3, and each being provided within one of the members 4 with a roller 8.

The broiler consists of a lower pan 9 hinged to which, at one end by means of a pin 10, is a cover 11, such cover being engageable by a catch 12 fastened to the member 9 for locking it in closed position with relation to the member 9. Said member 9 extends between the guide flanges 6 and is capable of sliding therebetween for the entire length of the frame 3. The pin 10 projects through the carriers 7 and is provided on each end with a thumb screw 12^a to hold it in position in said carriers 7. The member 9 is provided with a handle 13 at one end and a handle 14 at the other end and with a hook 15 at the same end that it is provided with the handle 13. The member 11 is provided with a hook 16 at the end opposite to the end on which the member 9 is provided with the hook 15.

The numeral 17 designates a handle member adapted to removably engage either the hook 15 or 16. When the broiler is to be used, the meat is placed in the member 9. The member 11 is then secured thereto by means of the catch 12. The handle 17 is then engaged with the hook 15 and used to move the broiler back and forth along the frame 3 over the burners 2. This moving operation is made easy by means of the rollers 8 and is guided by the flanges 6. When the meat is to be cooked on the other side, the member 9—11 is turned on its pivotal point 10 so that the member 11 comes over the flame from the burner 2. The handle member 17 is then disengaged from the hook 15 and engaged with the hook 16 whereupon the movement of the broiler can again be carried on over the blaze.

The numeral 18 designates a small opening adapted to be closed by a sliding cover or plug through which the juices may be withdrawn from the broiler after the cooking operation or before, if desired.

The above structure describes in the main

my improved attachment, but instead of the broiler, a waffle iron 19, as shown in section in Fig. 5, or a muffin or biscuit pan 20, as shown in section in Fig. 6, or any other desired form of pan can be used in place of the broiler, the construction and operation being the same.

In Fig. 7 is shown a section view of a toaster 21 provided with a cover 22 which 10 may be placed in the frame 3 with or without the roller and operating connections, if desired. This member may also be used as a cake pan, provided the toasting grate shown is removed.

15 From the foregoing description it will readily be seen that I have produced such a device as substantially fulfills the objects of the invention as set forth herein.

While this specification sets forth in detail 20 the present and preferred construction of the device, still in practice, such deviations from such detail may be resorted to as do not form a departure from the spirit of the invention, as defined by the appended claims.

25 Having thus described my invention, what

I claim as new and useful and desire to secure by Letters Patent, is:—

1. A device of the character described comprising a frame, carriers movable along said frame, a pin disposed in said carriers, a cooking utensil having one end pivotally mounted on said pin, said cooking utensil being arranged to be turned on said pin to reverse the position of the cooking utensil, as described. 30

2. A device of the character described comprising a frame, carriers movable on said frame, a pin disposed in said carriers, a cooking utensil pivotally mounted on said pin and being arranged to be turned on 40 said pin to reverse the position of such cooking utensil, such cooking utensil comprising two parts hinged together by said pin, as described. 35

In testimony whereof I affix my signature 45 in presence of two witnesses.

MABEL AARON.
